United States Patent Office

Des. 223,589
Patented May 9, 1972

223,589

COLUMN LAMP

Theodore Waddell, Via Rio Torto, Fiesole, Italy

Filed Nov. 9, 1970, Ser. No. 25,894

Claims priority, application Italy May 13, 1970

Term of patent 14 years

Int. Cl. D26—05

U.S. Cl. D48—20

Fig. 1

Fig. 2

Fig. 3

Fig. 4

Fig. 5

Fig. 6

FIG. 1 is a front elevational view of a column lamp showing my new design;

FIG. 2 is a side elevational view thereof;

FIG. 3 is a top plan view thereof;

FIG. 4 is a bottom plan view thereof;

FIG. 5 is a perspective view thereof; and

FIG. 6 is an enlarged perspective view thereof, the lamp being fragmentarily shown for convenience of illustration.

The annular bands of the lamp are shaded to indicate contrast.

I claim:

The ornamental design for a column lamp, as shown and described.
